UNITED STATES PATENT OFFICE

2,542,543

ELECTRICALLY HEATED WATER TANK

Eugene W. Losee, Hebron, Ill., assignor to Losee Products Co., a corporation of Illinois

Application January 8, 1947, Serial No. 720,816

15. Claims. (Cl. 219—39.)

1 This invention relates to a water heater, and particularly to an electric water heater of the displacement type.

This application is a continuation-in-part of my copending application Serial No. 568,233, filed December 15, 1944, now issued as U. S. Patent 2,422,492, dated June 17, 1947.

One feature of this invention is that it provides a water heater having an opening in the bottom thereof normally closed by a mounting member with the mounting member containing the electrical connections to the heater on its bottom surface and this bottom surface having a depending flange around the electrical connections to prevent their becoming wet by water accidentally leaking around the mounting member; still another feature of the invention is the provision of bolt openings or the like around the edge of the mounting member for attaching it to the water heater, and the provision of a second depending flange spaced inwardly of the bolt openings with the electrical connections being within this second flange in order that they may be protected from water accidentally leaking through the bolt holes; a further feature of the invention is that it provides a large well in the top of the heater extending into the water-containing portion of the heater and an improved readily-removable closure member for the water-containing portion providing ready access thereto; a still further feature of the invention is that it provides an improved electrical heating unit extending into the inner tank of the heater from the bottom thereof with the resistance element of the unit being spaced above the bottom of the tank throughout its entire length in order that the unit will not tend to overheat if lime, sludge, and the like is deposited on the bottom of the tank so as to inhibit the contact of the water with the bottom of the heating unit. Other features and advantages of this invention will be apparent from the following specification and the drawings, in which:

Fig. 1 is a vertical sectional view of a water heater embodying the invention; Fig. 2 is an enlarged vertical section through the upper large opening extending into the interior of the inner tank; Fig. 3 is a horizontal section taken along line 3—3 of Fig. 2; Fig. 4 is a vertical section taken along line 4—4 of Fig. 1 with portions broken away; Fig. 5 is a horizontal section taken along line 5—5 of Fig. 4; and Fig. 6 is a vertical section showing a modified form of heating unit and attached structure.

There are many places where a quantity of hot water is needed at periodic intervals, one such

place being in the milk house of the average dairy farm. There it is desirable to have five or ten gallons or so of hot water available at each milking period. Hot water may be desired for several purposes at each milking period, the principal need being for sufficient hot water to wash out thoroughly the milking utensils after the milking has been completed. Where the requirements are of this type with a relatively long period between withdrawals of hot water, an electric water heater is particularly satisfactory and efficient. The particular water heater shown in the accompanying drawings and subsequently described has been especially designed and is intended for use on dairy farms; but it will be apparent that the inventions hereinafter claimed are applicable to water heaters of this general type regardless of where they may be used.

The inventions disclosed and claimed herein are improvements in electric water heaters of the displacement type, heaters of this type being known to the art and in commercial use. Some of the advantages of a displacement heater and the general construction and operation thereof have been fully set out in the Joseph S. Losee Reissue Patent No. 21,893 of March 12, 1940. Accordingly, the general principles of operation and advantages of such a heater are only briefly mentioned at this time, reference being made to the above patent if further disclosure is desired.

Generally speaking, a water heater of this displacement type comprises an inner tank generally of non-corroding metal such as copper, a heat insulating enclosure for this tank, a base or support means, and water supply and delivery connections. The enclosure generally comprises heat insulating material such as rock wool, fiber glass, or the like and an outer metal shell, providing protection for the heat insulating material, of a metal which can be enamelled or finished in some desired manner to make the heater attractive in appearance. The water supply means may comprise a direct connection to a water pipe, but generally comprises an open vessel at the top of the heater acting both as a temporary reservoir and as a funnel with a pipe connection running down to a point adjacent the bottom of the inner tank to discharge cold water poured into the vessel at a point near the bottom of the inner tank. The delivery means comprises a pipe connection so arranged that hot water overflowing from the top of the tank (as cold water is supplied to the bottom thereof) is delivered outside of the tank through a discharge pipe at a height far enough above the floor that not only a pail, but also a wash tub, washing

tank of the kind used for washing milking machines, and the like may be conveniently filled. An arrangement of this general type is fully disclosed and claimed in the above mentioned Looee reissue patent.

Referring to the embodiment of the invention illustrated in Figs. 1 to 5 inclusive, the heater comprises a container having an inner metal tank 10 which may be of copper with a capacity of about ten gallons and a heat insulating enclosure surrounding it. Spaced from the inner tank 10 is an outer metal shell 11, which may be of sheet iron enamelled or otherwise appropriately finished comprising a main cylindrical body part 11a, a top part 11b, and a bottom part 11c. These various parts are welded or otherwise joined together and the bottom of the part 11a and the edge of the part 11c form a depending circular flange 12 on the bottom surface of the shell. The inner tank 10 is made of an upper part 10a and a bottom part 10b welded or otherwise joined at their contacting edges to form an outwardly extending flange 13 around the center of the inner tank 10, and the outer shell 11 is filled with an insulating material 14, such as rock wool or fiber glass or the like. While this insulating material may be of the so-called loose type, it is preferably in the form of blocks or bricks so that the heat insulating material at the top may be more conveniently removed for removal of the inner tank.

The bottom part 10b of the inner tank is provided with a substantially circular aperture or opening 15 at approximately the center of the bottom. The bottom part 11c of the shell is provided with a somewhat larger opening 16 arranged substantially concentrically with the first opening 15. The bottom opening 16 has an upwardly extending annular flange 17 with a cylindrical member 18 of heat insulating material being located inside the flange 17 and extending up to the bottom part 10b of the shell to prevent metal to metal contact between the inner tank 10 and the shell 11. Around the outer surface of the opening 15, there is located an annular supporting member 19 having an upwardly extending annular flange contacting the inner surface of the opening 15. A circular removable mounting member or plate 20 is adapted to be fastened to the lower surface of the supporting member 19 by means of spaced bolts 21 or the like. The plate 20, when in place, serving as a portion of the bottom wall of the water tank. A gasket 22 is provided between the supporting member 19 and the plate 20 in order to aid in preventing leakage between these two members. Mounted on the removable plate 20 and removable therewith is a depending drainage pipe 23 communicating with a hole 24 in the plate 20 to form a drain opening. The pipe 23 is normally closed by a removable plug 35. Located at one side of the pipe 23 is an electric heating member in the form of a U-shaped heating unit 25 having both ends fastened to the plate 20 and extending therethrough. The fastening means includes nuts 26. The heating unit 25 comprises an inner coiled resistance element 27 and an outer protective casing 28 substantially circular in cross-section. The lower ends of the resistance element 27 terminate a predetermined distance above the bottom of the inner tank 10, as an inch or two thereabove, and each end is connected to a relatively heavy wire 29, which extends down through the casing 28 and the removable plate 20. This spacing of the resistance

element ends above the bottom, and completion of the electrical connections through means which does not heat up provides protection for the resistance element 27 if the bottom of the inner tank is covered with a built-up layer of 5 sludge, lime or the like that may be flaked off by expansion and contraction of the unit 25 in the region of the element 27. If the resistance element 27 extended all the way to the bottom of the tank, the built-up sediment layer would prevent water from contacting the bottom of the heating unit and cooling the resistance element, and thereby cause the element to be more subject to overheating and burning out. As shown in 15 Fig. 4, the resistance element is protected up to the depth indicated by the broken line 30.

On the bottom of the removable plate 20, there is located a conventional thermostat unit 31 to control the operation of the heating unit 25 from 20 the heat of the water within the inner tank passing through the plate 20. The thermostat unit 31 is ordinarily connected in series with the resistance element 27 with the circuit being completed by an ordinary electric cord 30 which may be attached at its outer end to a source of electric power. All electric connections, including those to the cord 30, are located on the bottom of the plate 20. In case of failure in the heating means, the plate 20 may be removed with the heating unit 25, thermostat 31, and cord 30 and the whole may be checked for the source of failure either at the factory or other service station. The removable plate 20 has a depending outer flange 32 formed integrally therewith and surrounding the thermostat 31 and all electrical connections. This flange 32 serves to prevent moisture that might leak out around the gasket 22 from contacting the thermostat and the electrical connections.

The bolts 21 used in fastening the plate 20 to the supporting member 19 are held in holes extending through the plate 20. These holes provide other possible paths for moisture that might contact the electrical connections. In order to 45 protect the connections still further, a second depending flange 34 is provided spaced inwardly from the first flange 32 and the bolts 21. This second flange, as shown, constitutes a part of a second plate 33 fastened to the bottom of the 50 first plate 20 by spot welding or the like. The electrical connections are located within the second flange.

The bottom part 10b of the inner tank is provided with a depending flange 36 on the bottom thereof. This flange is engaged by a shoulder formed in an annular supporting member 31 of heat insulating material such as a resin or plastic. Spaced posts 37 are provided having their tops supporting the member 31 and flange 36, 60 and their bottoms resting on the bottom part 11c of the outer shell. This construction provides firm support for the inner tank 10.

The top 10a of the inner tank is provided with a large central opening 72 having an annular collar 38 therearound of copper or the like. This opening 72 is preferably in the neighborhood of 6 or 8 inches in diameter. The heat insulating enclosure 14 is provided with a well registering with this opening, the well being defined by a 65 cylindrical member 39 of sheet metal held in proper position by cooperation with the collar 38 and a shoulder formed on an annular member 40 of heat insulating material such as a resin or plastic, for example, rubber. The annular member 40 is located around an opening 73 formed in

the top portion 11b of the shell 11 and substantially concentric with the opening in the tank portion 10a. Another shoulder on the annular member 40 engages the edges of the top opening 13. This top part 11b has an upstanding flange 41 defining the opening and bearing against the other shoulder.

A gasket 42 of rubber or similar resilient material is located on top of the collar 38. The gasket 42 is adapted to receive the edges of a circular, inverted, dished closure member 43 having the shape of a disc. Immediately above the disc 43 is a second disc 44, also dished, with the convex surfaces of the two discs turned toward each other. The top disc 44 is provided with a centrally located collar 45 having a threaded inner surface adapted to engage a threaded cylinder 46. The collar 45 is fastened to the top disc 44 as by welding or brazing. The cylinder 46 has an enlarged top portion 47 provided with a roughened outer surface to facilitate manual rotation. The cold water supply means for the heater includes a pipe 48 passing through the cylinder 46 and both discs 43 and 44. At the top of the water pipe 48, there is located a surrounding tube 49 of metal. This tube 49 also passes through the cylinder 46 and bears against the bottom disc 43 to which it is fastened as by welding or brazing. On the inner surface of the cylindrical member 39 forming the well, there are located four spaced abutments 50 each having a depending inner flange 74 spaced from the cylinder 39. These abutments are in a substantially horizontal plane and serve as stop members for the edge of the top disc 44, which has an upwardly extending flange 75 adapted to be held under the flanges 74 on the abutments 50. The top disc 44 bears against these abutments as shown in Fig. 2 in order to provide backing means enabling the bottom disc 43 to be urged against the gasket 42. In order that the assembly of discs 43 and 44 and cylinder 46 may be easily withdrawn from and inserted into the well, the bottom disc 43 normally covers an area less than the area described by the inner surfaces of the abutment flanges 74. Also, the top disc 44 is provided with cut-out portions 51 at its edge each slightly larger than an abutment and spaced similarly to the spacing of the abutments. When inserting the unit into the well, the bottom disc 43 will pass between the abutments while the cut-out portions 51 may be passed around the abutments 50. When the top disc 44 is beneath the abutments, the disc may be turned a few degrees so that the cut-out portions no longer register with the abutments. In order to aid in turning the top disc, a pair of knobs 52 are provided on the top surface of the top disc so that these knobs may be grasped by the hands. After the discs 43 and 44 are in place, the cylinder 46 is turned so as to force the two discs 43 and 44 away from each other. This causes the bottom disc to bear against the gasket 42 and provide sealing contact therewith. The two discs 43 and 44, as shown in the drawings, are stressed somewhat so as to provide pressure against the gasket 42.

In addition to the cold water pipe 48, the supply means also includes a short tube 53 at the top thereof and extending thereabove. The tube 53 is preferably of a heat insulating material such as a resin or plastic. The tube 53 is preferably fastened to tube 48 by some means such as a clamp (not shown). Communicating with the top of the short tube 53 and adapted to rest on

the top of the annular member 40, there is located a vessel or open tank 54 having an inwardly turned top edge 55 to provide a splash shield. The bottom of the tank 54 has a downwardly extending cylindrical opening 56 whose bottom edge extends to a point adjacent to but spaced from the top of the first tube 48. In the top of the pipe 48, there is located a strainer means such as a filter screen 57 of cup shape having an annular marginal edge adapted to be held between the bottom of flange 56 and the top of the tube 48. As shown in Fig. 1, the top of the opening 56 is provided with a stopper 58.

The space between the two discs 43 and 44 provides a dead air space of high heat insulating value. The well above the top disc 44 is also a dead air space providing additional insulation to the interior of the water heater. This space is preferably filled with an insulating material (not shown).

A farmer can walk up to the heater with a bucket full of cold water, pour it in, set the bucket on the floor underneath the delivery spigot 59, and then pull out the stopper 58 in any appropriate manner. When this stopper is pulled out, the cold water flows through the pipe 48 into the bottom of the inner tank 10. An approximately equal quantity of water is displaced from the top of the tank and is delivered through the spigot 59 to the bucket or any other desired receptacle. The relationship between the water supplied to the tank and the water delivered therefrom is never precisely equal. The delivery action of the spigot 59, which is of inverted U-shape, acts as a siphon always drawing the water down to the bottom of the inner end of the siphon. Thus the amount of water standing in the expansion space is always added to the volume of water poured in. For all practical purposes, however, the volume of water delivered is equal to the volume of water poured in.

When it is desired to remove the discs 43 and 44 to provide access for cleaning the interior of the heater, the vessel 54 is first lifted off and the disc 44 is disengaged from the abutment 50 in the manner previously described. The discs 43 and 44, cylinder 46, tube 49, tube 53, pipe 48, and filter screen 57 are then removed as a unit from the tank. The inner walls of the tank can conveniently be inspected and any water therein drained off by removal of the bottom plug 35. The interior of the tank may be cleaned by reaching through the opening in the top thereof. The entire tank 10 may be removed from the heater by the method set out in my previously mentioned copending application No. 568,233. The spigot 59 has the same construction as the spigot shown and described in said copending application with the spigot comprising an inverted U-shaped tube having its outer end lower than its inner end and of smaller cross-sectional area than the remainder of the tube. The tube is surrounded by a rubber grommet 60 at the point where it passes through the outer shell 11. The inner end of the spigot 59 is held in a connector member 61 extending through the top portion of the inner tank 10. This connector has a tapered shoulder at the upper end thereof with the inner end of the spigot 59 having a slip fit within the cylindrical portion of the connector. This structure is described in greater detail in my copending application No. 568,233 of which this is a continuation-in-part.

The new water heater is supported on a number

of spaced legs 62 with each leg having the form of a rectangular U-shaped channel of tapering construction substantially larger at the top than at the bottom. The open portion of the U extends toward the center of the heater. The top of the leg 62 has one portion 63 supporting the bottom part 11c of the shell and another portion 65 engaging the side of the shell part 11a. The supporting portion 63 has a section 64 of its surface of arcuate shape terminating on its outer end in a shoulder at the side engaging portion 65 against which the flange 12 bears. The center of curvature of the arcuate section 64 is at approximately the top of the side engaging portion 65 of the leg. The bottom of each leg 62 is provided with a bolt 67 engaging a threaded hole in the bottom of the leg. The entire structure rests on these bolts and the bolts permit adjustment of the effective length of each leg so that the heater may be made level even when resting on uneven surfaces.

In the embodiment shown in Fig. 6, the heating member 100 passes through a hole 101 in the bottom 102 of the water tank, and is held by a top and bottom lock nut 103 and 103a, respectively, engaging threads on the bottom of the unit 100. Top and bottom gaskets 104 and 104a aid in preventing leakage of water through the hole 101. An electric cord 105 connects the heating unit 100 to a source of electric power. In order to prevent any moisture that might leak out around gaskets 104 and 104a from contacting the electrical connection of the cord to the heating unit, an outwardly curved bell-shaped flange 106 is provided attached to the bottom of lock nut 103a and surrounding the electrical connections on the bottom of the heating unit.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. A water heater or the like, comprising: a container including a bottom wall having an opening therein; an electric heating member extending through said opening; means for fastening the heating member in said opening, said means including a body portion on which is located said heating member; electrical connections on the bottom of said heating member; and a depending flange on said fastening means surrounding said electrical connections and extending below the bottom of said body portion.

2. A water heater or the like, comprising: a water container having an aperture in the bottom wall; a supporting member non-leakably fixed to the bottom of the container and having an opening in communication with the aperture in the container; a mounting member removably mounted on the supporting member; an electric heating member fixed to the body portion of the mounting member and extending into the interior of the container; a depending flange on the bottom of the mounting member extending below the bottom of said body portion and extending around the bottom of the electric heating member; and means for removably securing and sealing the mounting member to the supporting member.

3. A water heater or the like, comprising: a water container having an aperture in the

bottom wall; a supporting member non-leakably fixed to the bottom of the container and having an opening in communication with the aperture in the container; a mounting member removably mounted on the supporting member; an electric heating member fixed to the body portion of the mounting member and extending into the interior of the container; a depending flange at the edge of the mounting member extending around the electric heating member; a second depending flange on the mounting member spaced inwardly from the first flange and also extending around the electric heating member, both said depending flanges extending below said body portion; and means for removably securing and sealing the mounting member to the supporting member.

4. A water heater or the like, comprising: a water container having an aperture in the bottom wall; a supporting member non-leakably fixed to the bottom of the container and having an opening in communication with the aperture in the container; a mounting member removably mounted on the supporting member; an electric heating member fixed to the body portion of the mounting member and extending into the interior of the container; a thermostat fixed to the bottom of said body portion of the mounting member; means for removably securing and sealing the mounting member to the supporting member; a depending flange at the edge of the mounting member extending around the thermostat and electric heating member; and a second depending flange on the mounting member spaced inwardly from the first flange and also extending around the electric heating member and thermostat, both of said flanges extending below said body portion.

5. A water heater or the like, comprising: a container for liquid to be heated; a supporting member non-leakably fixed to the exterior side of a bottom wall of the container; a mounting member removably fixed to the exterior of the supporting member; an electric heating member fixed in the body portion of the mounting member and extending into the interior of the container; a thermostat unit removably fixed to the exterior of the body portion of the mounting member and arranged to be operated by heat passing through the mounting member from the liquid in the container, the thermostat being electrically connected with the heating member, said thermostat unit and heating member being removable with the mounting member as a unit; and a depending flange on the exterior of the mounting member extending around the bottom of the electric heating member and around the thermostat and extending below the bottom of said body portion.

6. A water heater or the like of the displacement type, comprising: an inner tank having an opening of substantial area in the top thereof; a heat-insulating enclosure for said tank, the enclosure having a well of substantial area registering with said opening; a closure member adapted to be received in said well to make sealing engagement therewith to close said opening; and water supply means including a pipe passing through said closure member and extending to near the bottom of the tank and provided with an opening for discharging water thereinto.

7. A water heater or the like of the displacement type, comprising: an inner tank having an opening of substantial area in the top there-

of; a heat-insulating enclosure for said tank, the enclosure having a well registering with said opening; a closure member adapted to be received in said well intermediate the ends thereof to make sealing engagement therewith to close said opening; and means at the top of the heater for supplying water to the tank and for delivering an approximately equal quantity of water therefrom, the supply means including a pipe passing through said closure member and extending to near the bottom of the tank and provided with an opening for discharging water thereinto.

8. A water heater or the like of the displacement type, comprising: an inner tank having an opening of substantial area in the top thereof; a heat-insulating enclosure for said tank, the enclosure having a well registering with said opening; a closure member adapted to be received in said well to make sealing engagement therewith to close said opening; and means at the top of the heater for supplying water to the tank and for delivering an approximately equal quantity of water therefrom, the supply means including a pipe passing through said closure member and extending to near the bottom of the tank and provided with an opening for discharging water thereinto, and a tank placed over and closing the outer end of said well to provide a dead air space above said closure member.

9. A water heater of the displacement type, comprising: an inner tank having an opening of substantial area in the top thereof; a heat-insulating enclosure for said tank, the enclosure having a well registering with said opening; a closure member adapted to be received in said well intermediate the ends thereof and to make sealing engagement with said well to close said opening; water supply means including a pipe passing through said closure member and extending to near the bottom of the tank and provided with an opening for discharging water thereinto, and means for holding the closure member in sealing engagement with the well.

10. A water heater or the like of the displacement type, comprising: an inner tank having an opening of substantial area in the top thereof; a heat-insulating enclosure for said tank, the enclosure having a well registering with said opening; a closure member adapted to be received in said well and making sealing engagement with said well to close said opening, said closure member comprising a pair of disc-like members having edges adapted to make sealing engagement with said well; water supply means including a pipe passing through said closure member and extending to near the bottom of the tank and provided with an opening for discharging water thereinto; and means adjacent said pipe for holding the closure member in sealing engagement with the well.

11. A water heater or the like of the displacement type, comprising: an inner tank having an opening of substantial area in the top thereof; a heat-insulating enclosure for said tank, the enclosure having a well registering with said opening, a closure member adapted to be received in said well and make sealing engagement with said well to close said opening, said closure member comprising a pair of dished disc-like members arranged approximately horizontal with their convex surfaces toward each other and having at least one disc edge adapted to make sealing engagement with said well; means for preventing

movement of the edges of the disc-like members away from each other; means for forcing the centers of the disc-like members away from each other to cause the edge of at least one disc-like member to press against the well by distortion of the disc-like members; water supply means including a pipe passing through said closure member and extending to near the bottom of the tank and provided with an opening for discharging water thereinto; and means adjacent said pipe for holding the disc-like members in sealing engagement with the well.

12. A water heater or the like of the displacement type, comprising: an inner tank having an opening of substantial area in the top thereof; a heat-insulating enclosure for said tank, the enclosure having a well registering with said opening; a closure member adapted to be received in said well and make sealing engagement with said well to close said opening, said closure member comprising a pair of dished disc-like members arranged approximately horizontal with their convex surfaces toward each other and having at least one disc edge adapted to make sealing engagement with said well; means for preventing movement of the edges of the disc-like members away from each other; means for forcing the centers of the disc-like members away from each other to cause the edge of at least one disc-like member to press against the well by distortion of the disc-like members; water supply means including a pipe passing through said closure member and extending to near the bottom of the tank and provided with an opening for discharging water thereinto; and means adjacent said pipe for holding the disc-like members in sealing engagement with the well and for forcing the centers of the disc-like members away from each other.

13. A water heater or the like of the displacement type, comprising: an inner tank having an opening of substantial area in the top thereof; a heat-insulating enclosure for said tank, the enclosure having a well registering with said opening; a closure member adapted to be received in said well and make sealing engagement with said well to close said opening, said closure member comprising a pair of dished discs arranged approximately horizontal with their convex surfaces toward each other and having at least one disc edge adapted to make sealing engagement with the inner surface of said well; means for preventing movement of the edges of the discs away from each other comprising a flange adapted to support the edge of the bottom disc and spaced abutments adapted to support the edge of the top disc, said top disc having cut-out portions at its edge each slightly larger than the abutments so that the cut-out portions may be passed around said abutments; water supply means including a pipe passing through holes in said discs at substantially the centers thereof extending to near the bottom of the tank and provided with an opening for discharging water thereinto; and a collar rotatably mounted around the pipe having its bottom bearing against the top of the bottom disc and having screw threads engaging screw threads on said hole in the top disc for forcing the centers of the discs away from each other to cause the edge of at least one disc to press against the well by distortion of the discs.

14. A water heater or the like of the displacement type, comprising: an inner tank having an opening of substantial area in the top thereof;

a heat-insulating enclosure for said tank, the enclosure having a well registering with said opening; a closure member adapted to be received in said well and make sealing engagement with said well to close said opening, said closure member comprising a pair of dished discs arranged approximately horizontal with their convex surfaces toward each other and having at least one disc adapted to make sealing engagement with the inner surface of said well; means for preventing movement of the edges of the discs away from each other comprising a flange adapted to support the edge of the bottom disc, said flange having a portion within the well against which the bottom disc bears in sealing engagement therewith; spaced abutments adapted to support the edge of the top disc; cut-out portions in the edge of said top disc each slightly larger than an abutment and spaced similarly to the spacing of the abutments so that the cut-out portions may be passed around said abutments, with said bottom disc normally covering an area less than the area described by the inner surface of said abutments; water supply means including a pipe passing through holes in said discs at substantially the centers thereof extending to near the bottom of the tank and provided with an opening for discharging water thereinto; and a collar rotatably mounted around the pipe having its bottom bearing against the top of the bottom disc and having screw threads engaging screw threads on said hole in the top disc for forcing the centers of the discs away from each other to cause the edge of the top disc to press against the abut-

ments and the edge of the bottom disc to press against the flange by distortion of the discs.

15. A water heater of the displacement type including: an inner tank having an opening of substantial area in the top thereof; a heat-insulating enclosure for said tank, the enclosure having a well registering with said opening; a closure member adapted to be received in said well and to make sealing engagement with said well to close said opening; water supply means including a pipe passing through said closure member and extending to near the bottom of the tank and provided with an opening for discharging water thereinto; and a strainer means at the inlet end of said pipe.
